United States Patent Office

Des. 204,903
Patented May 24, 1966

204,903

PORTABLE FLUORESCENT LIGHT

Donald Wayne Doman, Janesville, Wis., assignor to Servel, Inc., Freeport, Ill., a corporation of Delaware

Filed June 18, 1965, Ser. No. 85,798

Term of patent 14 years

(Cl. D48—24)

Fig. 4.

Fig. 5.

Fig. 7.

Fig. 6.

FIG. 1 is a front perspective view of a portable fluorescent light showing my new design;

FIG. 2 is a rear view thereof;

FIG. 3 is a bottom view thereof;

FIG. 4 is a side elevational view taken from the left of FIG. 5;

FIG. 5 is a front elevational view of the portable fluorescent light of FIG. 1;

FIG. 6 is a top plan view thereof, and

FIG. 7 is a horizontal sectional view taken on the line 7-7 of FIG. 4 and partly in full.

The essential features of the design reside in the portions shown in solid lines in the drawings.

I claim:

The ornamental design for a portable fluorescent light, substantially as shown and described.
